Original application November 13, 1939, Serial No.
304,150. Divided and this application August
11, 1942, Serial No. 454,405

3 Claims.

(CL. 125—11)

The present invention relates to dressing mechanisms and particularly to mechanisms for dressing the tip surfaces of wheels used in the grinding of gears. This application is a division of the application of the present inventor and Ernest Wildhaber, Serial No. 304,150, filed November 13, 1939.

In the grinding of longitudinally curved tooth tapered gears such as are used in automotive drives it is necessary to grind only the sides of the teeth because only the sides of the teeth of a pair of gears do the driving and automotive gears are made of sufficient size to readily carry any load likely to be encountered in use. Longitudinally curved tooth tapered gears have now been introduced into the aeroplane field, however, and different conditions are met with there. Aeroplane gears are heavily loaded to keep their size and therefore their weight at a minimum, and if the junctures of the bottom with the sides of a tooth space are not smooth, cracks tend to form at such junctures when the gears are under load, causing eventual failure of the gears. Hence, it has been found necessary to grind the bottoms as well as the sides of the tooth spaces of aeroplane gears to provide smooth bottom surfaces and smooth junctures of the sides with the bottoms, and to insure that the ground bottom surfaces blend with the ground side surfaces in smooth, uninterrupted curves. Moreover, for maximum strength, proper fillet radii must be ground at the junctures of the sides with the bottoms of the tooth spaces.

One object of the invention is to provide a dressing mechanism having means for dressing a round on a grinding wheel at the juncture of a side and the tip surface of the wheel so that a wheel may be provided which will be able to grind smooth sides and bottoms in the tooth spaces of a gear without any sharp corners at the junctures of the sides with the bottoms.

Still another object of the invention is to provide a dressing mechanism for simultaneously dressing the top of a grinding wheel and the rounds at the junctures of top with opposite sides of the wheel by a single swinging movement of a single dressing tool.

Other objects of the invention will be apparent hereinafter from the specification and from the recital of the appended claims.

In the drawings:

Fig. 1 is an elevational view, looking at the wheel end of a spiral bevel gear grinding machine of known construction and showing an end dressing mechanism constructed according to

one embodiment of the present invention mounted thereon;

Fig. 2 is a fragmentary transverse sectional view on an enlarged scale, through the end dressing mechanism and showing the position of the dresser in dressing the tip of a wheel;

Fig. 3 is a diagrammatic view showing the relation of the dressing diamond to the wheel in the dressing of the tip surface of the wheel, the view 10 being a cross-section taken in the plane of oscillation of the dressing tool;

Fig. 4 is a corresponding diagrammatic sectional view taken in the plane of the axis of the grinding wheel;

Fig. 5 is an elevational view of the dressing mechanism and its support, the view being taken looking in the direction of the arrow 5 of Fig. 2.

Fig. 6 is a sectional view through the support taken on the line 6—6 of Fig. 5;

Fig. 7 is an elevational view looking in the direction of the arrow 7 of Fig. 2, parts being broken away; and

Fig. 8 is a fragmentary elevational view, showing particularly the knurled knob for operating the end dresser and the stop for limiting its motion.

In the end dressing mechanism of the present invention, the dressing tool is mounted on a swinging arm and dressing is effected by oscillation of this arm. The swinging arm is mounted upon a support which is adjustable so that the axis of swing of the dressing tool may be inclined to a plane containing the axis of the grinding wheel to be dressed. When so positioned, the end dressing tool, as it swings across the tip of the grinding wheel, will move in a circular path inclined to the plane of the wheel and dress an elliptical surface on the wheel in the plane of the axis of the wheel. It has been found that such a surface provides a sufficiently flat tip surface on the wheel to grind flat bottoms in the tooth spaces of the gear and at the same time forms rounds on the wheel where the tip joins the side surfaces of the wheel so that the wheel will grind

40 sides on the tooth spaces which blend into the bottoms of the spaces. With the elliptical top surface, sharp corners at the junctures of the top and the sides of the wheel are avoided, thereby eliminating the possibility of formation of sharp corners in the tooth spaces of a gear ground with the wheel. Moreover, the rounds formed by the elliptical end surface of the wheel will produce fillet radii in the tooth bottoms that will give the gear teeth maximum strength.

At times it may be desirable to dress the tip

of the wheel to an absolutely flat surface instead of an elliptical surface and to provide rounds only at the juncture of this flat tip with the sides of the wheel. Adjustable stops are provided on the dresser to so limit its movement and operation.

The dresser shown is intended to be manually operated. It is mounted in a support which is adjustable laterally to determine the position of the center of arc of swing of the dresser, radially of the wheel axis to accommodate wheels of different diameters, and angularly to control the angle between the axis of swing of the dressing tool and the plane of the wheel axis, thereby to control the radius of the elliptical surface dressed on the wheel. In addition, the dresser support has an angular adjustment about the axis of the wheel so it may be positioned at a convenient point not to interfere with the gear being ground.

Reference will now be had to the drawings for a more detailed description of the invention.

The grinding wheel, which is to be dressed, is denoted at W. It is a rotary annular wheel having active side surfaces 31 and 32 and a tip surface 33.

The mechanism for dressing the wheel may be carried by a bracket 35 which may be mounted for angular adjustment about the axis of the wheel W in the manner described in application Serial No. 304,150 above mentioned. In Fig. 1 the bracket 35 carries not only the tip-dressing mechanism of the present invention, but also mechanism for dressing the sides of the grinding wheel. The side dressers are denoted at 79 and 80, respectively, and are supported on swinging arms 77 and 78, respectively, which may be actuated by any suitable means, such as described in application Serial No. 304,150, to dress the outside and inside surfaces 31 and 32 of the wheel simultaneously. The side-dressing mechanism forms no part of the invention claimed herein and for that reason will not be referred to further. The end or tip dressing mechanism is constructed as will now be described.

Mounted on the bracket 35 for angular adjustment thereon about the axis X of the grinding wheel is a plate 210 (Fig. 1). This plate is secured to the bracket 35 by bolts (not shown) which engage in the arcuate T-slot 211 which is formed on the front face of the bracket 35.

Mounted on the plate 210 for rectilinear adjustment thereon is a slide 212. This slide is secured in any position of its adjustment on the plate 210 by a T-bolt 213 whose head engages in an elongated T-slot 214 formed in the plate 210 (Figs. 1 and 5). A pointer 215 and a scale 216 are provided to enable this adjustment to be made accurately.

Mounted in the slide 212 for rotatable and axial adjustment therein is a cylindrical bar 220 (Figs. 1, 5 and 6). Keyed to this bar by means of a key 221 (Fig. 6) is a nipple 222. A cap member 223 is threaded on the outside of this nipple and fixedly secured thereto by a set-screw 224. A screw shaft 225 is rotatably mounted in a hole in the cap member 223 and is held against axial movement relative to the cap member by the washer 226 and the thimble 227 which abut, respectively, against opposite sides of the cap member 223 and which are pinned to the screw shaft 225. The screw shaft threads into a nut 228 that is threaded into a bore 229 of the bar 220. A pin 230 which is secured in the thimble 227 serves to rotate the screw-shaft. When the shaft is ro-

tated, the bar 220 is moved axially in the slide 212.

The bar 220 carries at its forward end a plate 235 (Figs. 2, 5 and 6). This plate has an opening 5 to receive the bar and has a pressed fit on the bar. As already stated, the bar 220 is not only slidably adjustable in the slide 212 but is also rotatably adjustable thereon. For the purpose of making the rotatable adjustment accurately a collar 240 is secured to the plate 235 by screws 241 (Figs. 1 and 6). This collar is provided with graduations which read against a pointer 242 that is secured to the slide 212. The rotatable adjustment may be made manually. After the adjustment has been made the bar is clamped in any adjusted position by the clamping blocks 237 and 238 (Fig. 5) which are rounded to engage the periphery of the bar and which are manipulated by the screw 239.

Mounted on the plate 235 for rectilinear adjustment thereon is a housing 245 (Figs. 1, 2, and 5). The adjustment of this housing on the plate may be made by means of a screw shaft 246 which is journaled in the plate and which threads into 25 a nut (not shown) that is secured to the plate 235. The screw shaft may be rotated by means of a knurled knob 247. The housing 245 is secured in any adjusted position on the plate 235 by a screw 249 (Fig. 2) which passes through an elongated slot 250 (Fig. 5) that is provided in the plate 235 and which threads into the housing 245.

Journaled in the housing 245 on spaced anti-friction bearings 250 and 251 (Fig. 2) is a shaft 252 to one end of which is secured an arm 253. A diamond holder 254, that carries the diamond 255 is mounted on this arm for angular adjustment thereon. This angular adjustment permits of adjusting the diamond so that it extends at right angles or any other desired angle to the tip surface 33 to be dressed. The diamond holder may be secured in any adjusted position by a bolt 256 which passes through an arcuate slot 257 in the arm 253 and which threads into the diamond holder.

The angular adjustment of the plate 210 on the bracket 35 (Fig. 1) and the angular adjustment of the plate 235 and bar 220 on the slide 212 (Fig. 5) permit of positioning the housing 245 (Fig. 2) so that the axis of the shaft 252 is inclined at any desired angle to the tip surface 33 of the grinding wheel W to be dressed. The rectilinear adjustment of the slide 212 on the plate 210 permits of adjusting the diamond 255 in accordance with the height of the wheel to be dressed. The rectilinear adjustment of the bar 220 in the slide 212 permits of this setting being made more precisely, as to compensate for wear of the wheel. The rectilinear adjustment of the housing 245 on the plate 235 permits of positioning the diamond so that the center of swing of the diamond will be midway the sides of the wheel.

When the diamond 255 is positioned so that the axis of the shaft 252 is inclined, as shown in Fig. 2, at other than a right angle to a plane containing the axis of the grinding wheel, it will dress an elliptical curve on the tip of the wheel. In a plane of the diamond rotation the diamond will, of course, trace a circular arc 260 (Fig. 3) 65 on the tip surface of the grinding wheel but in the axial plane of the grinding wheel, as illustrated in Fig. 4, the path of movement of the diamond will be an ellipse as denoted in heavy lines at 260'. The elliptical curve provides a substantially flat surface on the top of the grinding

wheel while providing rounds at the sides of the wheel which blend into the side surfaces 31 and 32 of the wheel without any sharp corners. Thus the dressing mechanism of the present invention permits of dressing the grinding wheel so that suitable fillet curves are produced at the root lines of opposite sides of each tooth space of a gear or pinion ground with the wheel while the bottoms of the tooth spaces are ground substantially flat. At the same time no sharp corners will be formed at the junctures of the bottoms with the sides of the teeth. Hence sources of possible cracks in the gear teeth will be eliminated.

A knurled knob 271 is keyed to the shaft 252 to permit manual rotation of the shaft to effect the dressing of the tip of the grinding wheel as described.

Adjustable stops 265 and 266 that thread into lugs or ears 267 and 268, respectively, formed on opposite sides of the housing 245 serve to limit the swinging movement of the end dresser. These stops are adapted to be engaged, respectively, with opposite sides of a lug 270 (Figs. 2, 7, and 8) that is formed on the knurled knob 271.

Mounted in the lug 270 is a spring pressed detent 275 which is engageable in a recess 276 formed in a collar 277 that is fastened in any suitable manner to the housing 245. A coil spring 279 serves to hold the detent 275 in engagement with the notch or recess 276. A knurled knob 280 is secured to the detent to enable the operator to retract the detent from engagement with the notch 276 and to allow him to rotate the detent when retracted. The knob 280 has four equiangularly spaced notches 282 formed on its periphery. A pin 283, which is secured in the lug 270, is adapted to be engaged selectively in one of these notches to hold the knob 280 and detent 275 in any one of the four different positions in which the detent may be engaged with the recess 276. In addition, the knob 280 may be pulled out and rotated to a position where its bottom face will ride on the tip of the pin 283 so as to hold the detent out of engagement with the recess 276.

When the detent 275 is retracted far enough so that the knob rides on the top of the pin 283, the shaft 252 may be swung through the full angle determined by the settings of the stops 265 and 266. When the pin 283 is engaged in one of the notches 282 of the knob 280 so that the detent is in the position shown in Fig. 7 then the shaft 252 can be rotated in a counterclockwise direction until the stop 265 strikes the lug 270, but it cannot be rotated in a clockwise direction from the position shown because the detent prevents such movement. On the counterclockwise movement the detent simply rides up out of the notch 276. By disengaging the detent from the notch 276 and rotating the knob 280 through an angle of 180° from the position shown in Fig. 7, the detent can be positioned to prevent counterclockwise movement of the shaft from the position shown while permitting clockwise movement through the distance limited by the stop 266. When the detent is adjusted to a position at right angles to that shown in Fig. 7, it locks the shaft 252 against rotation in either direction.

When the detent is held out of engagement with the notch 276, full swing of the diamonds across the end of the wheel to dress the tip of the wheel and rounds at the junctures of the sides of the wheel with the tip is allowed. When the detent is in the position shown in Fig. 7 or in a position at 180° to that shown in Fig. 7, only a limited swing of the diamond 255 is possible and such

swing may be employed simply to dress a round at the juncture of the tip 33 of the wheel with one or other side 31 or 32 of the wheel. When the detent is in a position at 90° from the position shown in Fig. 7, then no swing of the diamond is possible but the diamond may be moved by the knob 247 to dress a plane tip surface on the wheel. This may be desirable for dressing wheels for automotive work. It will be seen, therefore, that the present invention provides a dressing mechanism capable of a wide range of work.

While the invention has been described in connection with a dressing mechanism for dressing an annular wheel, it will be understood that in principle the dressing mechanism of this invention may be employed in dressing other types of wheels also. It will further be understood that while the invention has been described in connection with a particular embodiment thereof, it is capable of various further modifications. The present application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. In apparatus for dressing the tip surface of a rotary grinding wheel, a support, a shaft oscillatably mounted in said support, an arm secured to said shaft, a dressing tool mounted on said arm, a block secured to said shaft, a pair of stops adjustably mounted in said support and adapted to engage, respectively, opposite sides of the block to limit swinging movement of the shaft in opposite directions, auxiliary means carried by the block which is engageable with the support to limit swinging movement of the shaft in one direction, means for oscillating the shaft to effect circular arcuate movement of the dressing tool, and means for moving said support in a rectilinear direction to effect straight line movement of the dressing tool.

2. In apparatus for dressing the tip surface of a rotary grinding wheel, a support, a shaft oscillatably mounted in the support, an arm secured to the shaft, a dressing tool mounted on the arm, means for swinging the arm to effect circular arcuate movement of the dressing tool, means for effecting rectilinear movement of the support to effect a straight line movement of the dressing tool, a block secured to the shaft, adjustable stops secured to the support and adapted to engage opposite sides of the block to limit movement of the shaft in opposite directions, a detent mounted in the block, a recess in the support with which the detent is engageable, a spring normally holding the detent in engaged position, said detent being beveled at its engaging end, and means for holding the detent in disengaged position.

3. In apparatus for dressing the tip surface of a rotary grinding wheel, a slide, a shaft oscillatably mounted in the slide, adjustable stops carried by one of said parts and a relatively fixed stop carried by the other of said parts and adapted to be engaged with one or other of the adjustable stops on swinging movement of the shaft to limit the angle through which the shaft may be swung,

a detent carried by one of said parts and adapted to be engaged with the other part in selectively different positions, said detent in one position of its engagement limiting the movement of said shaft in one direction to less than the angular movement permitted by the setting of said adjustable stops, and in another position of its engagement preventing movement of the shaft relative to the slide, an arm secured to the shaft,

a dressing tool mounted on the arm in offset relation to the axis of the shaft, a support on which the slide is rectilinearly movable, means for moving the shaft to effect swinging movement of the dressing tool in a circular arcuate path, and separate means for moving the slide rectilinearly on the support to effect rectilinear movement of the dressing tool.

LEONARD O. CARLSEN.
